ROLL-DRESSING APPARATUS

James A. George, Brackenridge, Pa.

Application September 30, 1932
Serial No. 635,518

6 Claims. (Cl. 51—252)

My invention relates to apparatus for dressing and truing the rolls of steel-rolling mills, and includes a flexible grinding device and means for shifting the grinding device to and fro across the face of a roll. Indeed, I provide a grinding device for each of the co-operating rolls in a mill, and, due to the novel structure of my apparatus, the rolls of the mill are dressed and maintained in finely dressed condition while in service.

10 In general, apparatus for the dressing of rolls in the above-mentioned manner have been employed hitherto; for example, apparatus including a grinding wheel has been used for years—the grinding wheel is rotated and shifted axially across the face of the roll being dressed. In another known type of roll-dressing apparatus a block of abrasive material is pressed snugly against the face of a rotating roll, and is automatically shifted back and forth across the roll.

15 Among all the prior roll-dressing apparatus, however, there is none which can be satisfactorily employed in dressing the rolls of a hot-mill in service. It will be understood that the rolls of a hot-mill are subject to a surface temperature of 20 500 or more degrees Fahrenheit, and, as in service the stock being rolled enters and leaves the pass between the rolls, the rolls "jump" or "spring" a small fraction of an inch. Accordingly, a grinding wheel, or a block of abrasive material, held against the face of a hot-mill roll in service tends to nick or to scar the roll when it "jumps." In the main it is for these reasons that, hitherto, it has been practically impossible to dress the rolls of a hot-mill while in operation—30 35 the practice having been to cease the rolling operation of the mill and to run it idly while its rolls are being dressed.

In accordance with the present invention, I provide a grinding device which automatically adjusts itself upon the curved face of the roll; when the roll "jumps," my grinding device readily yields, so that the roll surface is not nicked or scarred. Accordingly, my invention permits hot-mill rolls to be dressed and to be maintained in dressed condition while the mill is in operation. This fact, of course, makes for economy in large measure; the hot-mill may remain in continuous service, and at all times the surfaces of its rolls may be maintained in nicely dressed condition.

50 My invention consists in providing an endless, flexible member bearing a succession of grinding blocks. The flexible member advantageously comprises a chain structure which permits a plurality of the abrasive blocks it carries to adjust

themselves to the curvature of the roll, and to bear with self-adjusting pressure against the surface of the roll. The apparatus of the invention includes means for effecting the travel of the endless chain, so that the abrasive blocks 60 move counter to the movement of the roll surface against which they bear. Means are also provided for automatically effecting the lateral reciprocation of the travelling chain of blocks across the face of the roll being dressed. It is 65 further characteristic of my apparatus that it may be removed from the mill readily and in a moment, to permit replacement of rolls, and this is greatly advantageous over the now usual forms of apparatus which may not be removed, except 70 with the expenditure of a great deal of time and effort. Other objects and advantages of my invention will be found in the following specification.

In the accompanying drawings I illustrate 75 a single pass hot-mill, and show in association therewith dressing apparatus embodying my invention. A travelling chain grinding device is provided for each of the two rolls of the mill, but it is to be understood that one grinding device 80 can be employed, and applied first to one and then to the other of the rolls of the mill. Figure I shows a hot-mill fragmentarily in elevation at the leaving end of its pass, and illustrates my roll-dressing apparatus applied thereto; Figure II is a view in plan from above of the apparatus shown in Figure I; Figure III is a view of the apparatus, partly in cross section and partly in side elevation, taken on the plane III—III of Figure II; Figure IV is a view in cross-section, 90 taken on the plane IV—IV of Figure II, and showing to larger scale the structure of the endless-chain grinding device; Figure V is a view, partly in side elevation and partly in cross-section, of two grinding blocks and the associated block-carrying chain; and Figure VI is a view in longitudinal section of one of the grinding blocks and the chain elements which support it.

The reference numerals 1 and 2 are applied respectively to the two rolls of the single pass 100 mill shown in the drawings; numerals 3 and 4 are applied to the opposite frames, in which the rolls 1, 2 are trunnioned, and the arrow on each roll in Figure I indicates the direction of roll rotation. Adjacent the face of each roll a carriage is supported, and each carriage includes abrasive means for dressing the surfaces of the rolls. To further an understanding of the invention, it may be advantageous to consider first the carriage structure. Turning to Figure IV, 110

it will be seen that the roll 1 is fragmentarily indicated in vertical section, together with the carriage which is associated with such roll. The carriage comprises a frame 5 that is rectangular 5 in front elevation (Figure I), and is curved in side elevation in approximate conformity to the curvature of the roll, adjacent to which it is mounted (Figure IV). An endless, flexible chain 6 is trained over co-operating sprocket wheels 7 and 8 which are revolubly mounted in frame 10 5. The flexible chain 6 carries a succession of abrasive blocks 9, the abrasive material of which the blocks are fashioned being any one of the materials now commonly used in roll-dressing 15 tools. Each block 9 is secured in a socket member 10; each socket member includes in structure opposite side walls which are drawn against the inclined side walls of the block 9 (Figure V); adjacent each end of the block 9 a screw 20 or bolt 11 serves as the means for securing the side walls of the socket member tightly against the block (Figure VI), and two chain elements 12 are integrated with the base of socket member 10, to the end that the socket member may be, 25 as indeed it is, secured to the flexible chain 6. Thus, blocks 9 of abrasive material are secured to the chain at intervals in its extent.

Due to the flexible structure of the block-armed chain 6, several of the blocks 9 in its inner reach 30 are adapted to adjust themselves with their effective faces aligned in concave curvature and shaped to the convex curvature of roll 1, and, in this case, the design of the chain is such that four blocks 9 in the inner reach of the chain bear 35 against the face of the roll (Figure IV). In service the roll 1 turns in the direction of arrow a, and, manifestly, the four abrasive blocks 9 in bearing against the face of the roll effect a dressing of so much of the roll's face as they engage, 40 while the roll is rotating. By reciprocating the carriage frame 5 longitudinally of the rotating roll, it is evident that the entire face of the roll may be treated by the abrasive blocks. As will presently appear, I provide means for automatically effecting such reciprocation of the carriage.

It will be understood that in supporting a flexible succession of abrasive blocks against the face of the roll, and in providing a yielding or flexible mounting (chain 6) for the blocks, I overcome the 50 objections to prior roll-dressing apparatus. In my apparatus a relatively large area of contact between roll and abrasive material is afforded, so that the abrading effect is not concentrated upon a small area of the roll's surface, as is the case in apparatus including a rotating grinding wheel. Additionally, the flexible nature of the chain 6—the characteristic which admits of self adjustment of the blocks against the roll—permits the apparatus to operate while the hot-mill is in 55 service. When the roll "jumps" in the manner alluded to above, the several blocks 9, bearing against the roll, readily and in an instant conform themselves to the roll in its shifted position.

I have discovered that from time to time during the operation of the mill the chain of blocks 65 9 may be caused to travel in a direction counter to that in which the surface of the roll moves. Accordingly, a high effective grinding speed may be obtained, without danger of scarring the roll. Indeed, by controlling the velocity of travel of the chain 6, I can regulate the grinding or dressing effect to which the roll is subjected while in service, it being understood that the velocity of the 70 roll in service is more or less constant, or is de-

pendent upon factors other than the conditioning of the roll's surface.

One of the sprocket wheels 7, 8 is power rotated, to effect travel of the chain 6 and blocks 9, in the direction of the arrow b in Figure IV. The particular one of the two sprocket wheels 7, 8 which is power driven is the one which effects the pulling of the chain or blocks over the face of the roll, as distinguished from the other sprocket wheel which, if driven, would tend to push the chain of blocks over the roll surface. Specifically, the lower sprocket wheel 8 is driven, in the case of the upper roll 1, and the upper sprocket wheel 7 is driven, in the case of the lower roll 2 (cf. Figure I). Thus in the case of each roll the blocks 9 are drawn progressively into contact with the roll. In group arrangement the blocks conform themselves to the curvature of the roll, and sweep over the face of the roll in a direction counter to the direction of travel of the roll's face.

The sprocket wheel which rotates idly in response to chain travel—the sprocket wheel 7 in Figure IV—is organized with means for adjusting the tension or play in chain 6, to the end 100 that the correct flexibility or tautness of the chain may be provided for a roll of given size. Such means comprise an eccentric journal 7a, integrated with the axle 7b upon which the sprocket wheel 7 is mounted. The axle 7b is 105 normally stationary in frame 5, and the sprocket wheel 7 rotates, together with an interposed bushing 7c, upon the eccentric journal 7a. Manifestly, the angular adjustment of the shaft 7b in the frame 5 shifts the center about which the sprocket 110 7 turns, and, accordingly, the tautness of the chain 6 may be regulated.

Turning now to Figures I and II, other phases of the invention will be considered. As has been already indicated, a carriage (5) with its chain 115 of roll-dressing blocks is provided for each of the rolls 1 and 2. Each carriage is provided with a pair of oppositely-extending stems 13, and a rod co-operates with the stems 13, to support the carriage adjacent the face of the roll. Indeed, the 120 supporting rod for each carriage comprises two sections 14 and 15, and the inner ends of the two sections are bored, to receive the stems 13 of the associated carriage. Pins or bolts 16, extending diametrically through the rod sections and stems, 125 serve to integrate the carriages with their supporting rods 14, 15.

The rods 14, 15 are, conveniently, supported in the frame members 3 and 4 of the rolling mill; in such frame members the rods are free to turn 130 about their axes and to move longitudinally of their axes. The opposite ends of the rods (14, 15) are provided with counterweighted arms 17, and such is the location of the counterweighted arms that they tend to turn axially the rods 14, 15, 135 and to swing the carriages against the rolls with which they are associated. Upon considering Figures II and IV, it will be perceived that the direct effect of the counterweighted arms is to press 140 yieldingly the abrasive blocks 9 carried by the inner reach of each chain 6 against the face of its associated roll. The organization of the supporting rod 14, 15 is such in the case of the upper roll 1 that the axis of the supporting rod lies slightly above the middle of carriage 5, while in 145 the case of the lower roll 2 the rod 14, 15 supports the carriage 5 adjacent its top. The particular location of the supporting rod with respect to the carriage is a matter to be determined upon a consideration of the particular mill to which my ap- 150

paratus is applied,—the direction of roll rotation, the radius of the roll, and the structure of the mill frame being the things upon which the determination is made.

5 Throughout a portion of its length each rod section 15 is so provided with teeth as to constitute a rack. A pinion 18 is provided for each rod section 15; the pinions 18 are severally secured upon shafts 19 and 20, and are in mesh with the rack portions of the respective rod sections 15. The shafts 19 and 20 are trunnioned respectively in brackets 21 and 21a, such brackets being secured to the frame 4 of the mill, as shown in Figure III. I provide means for automatically rotating the shafts and pinions, first in one direction and then in the other, to effect the axial reciprocation of the supporting rods 14, 15. The range of rotation, i. e. the number of revolutions of each pinion, is so determined that the carriages 5 are swept to and fro across the faces of the rotating rolls 1, 2. It may be well to remark now, that the teeth formed in rod sections 15 are radial in section, to permit the rods 14, 15 to turn under the influence of counterweighted arms 17 for the purpose aforesaid (cf. Figure III).

The shafts 19 and 20 are provided with sprocket wheels 22 and 23 respectively, and a manually-operated clutch 24 is organized with each of sprocket wheels 22 and 23, so that at the will of the attendant the sprocket wheels may be independently united with or disengaged from the shafts 19, 20. Mounted upon a suitable base 25 is a motor 26 which drives a countershaft 27, and the speed of shaft 27 is reduced by means of gear-box 28. Shaft 27 carries two sprocket pinions 29, and two chain belts are trained severally over these pinions and the respective sprocket wheels 22, 23. Shaft 27 is coupled to an auxiliary gear-box 30, and extending from such gear-box, and adapted to be rotated in response to the rotation of shaft 27, is a shaft 31 which carries an arm 32. The electrical wiring for motor 26 includes a reversing switch 33 which is operated by the shifting of its switch-arm 34. The specific electrical wiring for the motor is not shown, it being merely a matter for the electrician; suffice it to say, when the switch-arm 34 is in elevated position, the motor 26 is caused to turn in one direction, and, when the switch-arm is in lowered position, the motor is driven in the opposite direction of rotation. The operation of motor 26 effects the turning of arm 32 (Figure II), and in its turning the arm 32 engages and "throws" the switch arm 34. Thereupon, the rotation of the motor is reversed; consequently the arm 32 turns in the opposite direction, until it engages and throws the switch arm 34 back into its first-mentioned position. It will now be manifest that the arm 32 is adapted automatically and in definite period to reverse the motor 26. Thus the shaft 27 turns through a range of rotation, first in one direction, and then in the other, and the sprocket wheels 22, 23 are positively rotated in accordance with the range of alternate rotations of shaft 27. Accordingly, the shafts 19, 20 are alternately rotated clockwise and counterclockwise, and the pinions 18 effect the reciprocation of the carriage-supporting rods 14, 15. It is simply a question of designing the gear ratios of gearboxes 28 and 30 and of adjusting the parts, to so determine the alternate rotations of shafts 19 and 20, that carriages 5 are swept back and forth across the entire length of the rolls 1, 2,

and to adjust the range of carriage reciprocations for rolls of any given length.

By means of the clutches 24, the reciprocation of each carriage 5 is controlled; indeed, either carriage may be stopped at any point in its travel longitudinally of the roll, and may be allowed to remain at such point for any desired time interval. As a matter of fact, the rolls require more dressing at their end regions than in their central portions, and my apparatus is particularly adapted to such condition; that is, the carriage may be brought to the position where the roll requires greater treatment, and, by releasing the clutch (24), the carriage is caused to remain there, until such region of the roll is properly dressed.

Turning now to the means for effecting the travel of the block-armed chains 6: A motor 35 is mounted on base 25, and, by means of a gearbox 36, the motor drives a shaft 37 (Figure II). A sprocket wheel 38 is mounted upon shaft 37, and a clutch 39 serves to unite the sprocket wheel to the shaft, as is desired in service. Secured to the rolling mill frame 4 (Figure III) are two brackets 40, one located below each of the carriage-supporting rods 15. A sprocket wheel 41 is revolutely mounted in each bracket 40; the lower of the two sprocket wheels is driven directly from sprocket wheel 38, by means of a chain belt 42. The upper sprocket wheel 41 is driven by a chain belt 43 whose movement is derived from shaft 37, and is under the control of a clutch 44. A squared shaft 45 extends slidably through each sprocket wheel 41, and each shaft 45 is secured to the axle of one of the sprocket wheels 7, 8 of each carriage 5 (cf. Figure I). A readily removable universal joint 46 affords the union of the square shafts 45 with the sprocket wheel axles. Accordingly, rotation of the shafts 45 produces the travel of the block-armed chains 6, in the manner alluded to in the fore part of this specification, and the rotation of the shafts 45 is subject to the control of clutches 39, 44. As the carriages 5 are reciprocated along the face of the rolls, the square shafts 45 slide in sprocket wheels 41, so that the lateral movement of the carriages does not interrupt the travel of the abrasive blocks 9.

A further advantage is found in my apparatus. From time to time it becomes essential to change the rolls in the rolling mill, and it is necessary, to facilitate the operation, to clear the roll dressing apparatus away from the rolls. In such case, the bolts 16 are withdrawn from the rod sections 14, 15, and the rod sections are each slid outwardly of the respective frame members 3, 4 in which they are mounted. Thus, the stems 13 are released from their supporting rods 14, 15, and the carriages 5 are lifted away from the rolls—it being understood that the universal joints 46 are also disengaged from the axles of sprocket wheels 7, 8. So, the carriages 5 are moved from the rolls, and the supporting rods 14 and 15, together with the shafts 45, are slid outward and away from their place adjacent the rolls. In brief, the rods 14, 15 constitute separable supports for the roll-dressing tools, and, as such, they permit the roll-dressing apparatus in a minute to be removed for interchanging the rolls of the mill.

It will, of course, be understood that the invention is applicable to "three-high" mills—that a carriage 5 may be organized with each roll of the mill regardless of the number of rolls in the mill. Additionally, I contemplate that the means for driving the block-armed chain and for recipro-

cating the carriages 5 may, in accordance with engineering practice, be driven by the rotating rolls of the mill.

I claim as my invention:

5. 1. In roll-grinding apparatus for rolling mills, the combination of a frame, a carriage on said frame, and means for reciprocating said carriage transversely of the frame; a plurality of rigid heat-resisting blocks of abrasive having grinding 10 surfaces of substantial extent relatively to the circumference of the roll to be ground, said rigid blocks being articulated together in a flexible unit supported by said carriage and adapted to be drawn circumferentially of the roll while maintained in contact therewith, and means for maintaining such flexible unit in contact with the roll to be ground throughout a substantial portion of the circumferential extent thereof while allowing the unit to advance under traction, the 20 organization of the unit being such that under traction the succession of blocks automatically shapes itself to the contour of the roll and the grinding faces of the blocks individually shape themselves automatically to the contour of the 25 roll.

2. Roll-dressing apparatus for rolling mills, said apparatus including a frame, a carriage reciprocable transversely of the frame, a flexible member supported at spaced-apart points in said carriage, said flexible member being armed with a succession of heat-resisting abrasive blocks adapted to extend circumferentially of the roll to be dressed, said blocks severally being provided with concave grinding faces, said flexible 30 member and the organization of blocks with which it is armed being such in structure that the succession of blocks is adapted to extend with said grinding faces aligned in concave curvature, and means for maintaining such block-armed flexible 35 member against the face of said roll, whereby the succession of blocks, under the influence of said means, automatically shapes itself to the contour of the roll, and the concave grinding faces of the blocks automatically adjust themselves sever- 40 ally to the contour of the roll.

3. In roll-dressing apparatus for rolling mills, the combination of a frame, supporting means reciprocable transversely of the frame, means for reciprocating said supporting means, an articulated chain armed with a succession of heat-resisting abrasive blocks, said chain being secured at spaced-apart points to said supporting means, whereby said blocks are adapted to extend circumferentially of the roll to be dressed, said blocks 50 severally being provided with concave grinding faces of substantial extent relatively to the circumference of said roll, means for maintaining said block-armed chain against the face of said roll, the axes of articulation of said chain extending parallel to the axis of said roll, and the organization of blocks with which said chain is armed being such that the succession of blocks is adapted to extend with said grinding faces aligned in concave curvature, whereby the suc- 55 cession of blocks, under the influence of said means, automatically shapes itself to the contour of the roll, and the concave grinding faces of the blocks automatically adjust themselves severally to the contour of the roll.

70. 4. In roll-dressing apparatus for rolling mills, the combination of a frame, supporting means

reciprocable transversely of the frame, and means for effecting reciprocation of said supporting means, an endless flexible member armed with a succession of heat-resisting abrasive blocks, said flexible member being secured at spaced-apart points to said supporting means, whereby said succession of blocks is adapted to extend circumferentially of the roll to be dressed, said blocks severally being provided with concave grinding faces of substantial extent relatively to the circumference of said roll, said flexible member and the organization of blocks with which it is armed being such in structure that a plurality of blocks is adapted to extend with the grinding faces thereof aligned in concave curvature, means for maintaining a plurality of blocks against the face of said roll while allowing the endless member to advance under traction, whereby the succession of blocks advancing under traction automatically shapes itself to the contour of the roll and the concave grinding faces of the blocks individually adjust themselves automatically to the contour of the roll.

5. In a roll-dressing machine for rolling mills, the combination of a frame, two supports mounted in spaced-apart relation in said frame, said supports being movable in said frame axially of the roll to be dressed, and means for effecting the movement of said supports, a flexible member mounted upon and extending between said supports, and a series of heat-resisting abrasive blocks carried by said flexible member and adapted to extend circumferentially of said roll, the interval between said spaced-apart supports being less than the effective length of the flexible 100 member extending between the supports, and said flexible member and the organization of blocks carried thereby being such that said flexible member is adapted to curve from the plane of its extent inward of said supports, whereby several blocks of the series carried by such flexible member are adapted to adjust themselves with their effective faces (considered collectively) 105 in concave curvature and shaped to the convex curvature of said roll.

6. In a roll-dressing machine for rolling mills, the combination of a frame, an endless flexible member, a series of heat-resisting abrasive blocks carried by said member and adapted to extend circumferentially of the roll to be dressed, two 125 spaced-apart supports rotatably mounted in said frame, said spaced-apart supports being jointly movable axially of said roll, means for effecting such movement of the supports, said endless flexible member being trained over said supports and providing an inner reach in the member adapted to extend adjacent the face of said roll, means for effecting the travel of said flexible member, the interval between said spaced-apart supports being less than the effective length of the flexible 130 member in its inner reach, and the structure of said flexible member and the organization of blocks carried thereby being such that said flexible member is free to curve from the plane of its extent in said inner reach inward of said supports, whereby several blocks of the series are adapted automatically to adjust themselves with their effective faces (considered collectively) 135 in concave curvature and shaped to the convex curvature of said roll.

JAMES A. GEORGE.
